WALL SWITCH

Humphrey N. Heasty, Milwaukee, Wis.

Application April 30, 1945, Serial No. 590,988

12 Claims. (Cl. 200—155)

1

This invention relates to improvements in wall switches.

It is a primary object of the invention to provide a novel and improved wall switch which, although mechanical, as distinguished from mercury switches, will nevertheless be smooth and noiseless in operation.

A further very important object of the invention is to provide a switch which will be extremely effective and yet extremely inexpensive and more easily operable than presently available wall switches.

Other objects will appear to those skilled in the art upon analysis of the following disclosure of the invention.

In the drawings:

Fig. 1 is a view in perspective showing a complete switch assembly as it appears in readiness for mounting in the conventional outlet box.

Fig. 2 is a view taken in section through an outlet box and switch plate showing my improved switch assembly mounted therein, the switch assembly being largely illustrated in side elevation.

Fig. 3 is a view in perspective showing the face plate with the operating disk of my improved switch projecting therethrough.

Fig. 4 is a fragmentary view of my switch assembly showing certain of the parts in rear elevation, other parts being broken away to expose the interior structure.

Fig. 5 is a detailed view of the switch rotor in elevation, a portion thereof being broken away to expose its interior construction.

The parts are identified by the same reference characters throughout the several views.

My improved switch may be assembled in a conventional outlet box 6 having a conventional switch plate 7. The bracket 8 may conveniently be made of sheet metal to terminate in oppositely directed mounting flanges 9. In the normal mounting of the bracket, the portion 10 thereof will be at the bottom, although this is not essential. Regardless of its location, the portion 10 of the bracket provides a base to which are screwed the dielectric blocks 11, 12. Upon these blocks are carried the flanges 13 of the switch contact arms 14, 15, the contact portion of each being preferably provided by a boss at 16 integrally formed therein. The electrical connection to the respective contacts may be made by anchoring a wire beneath the head of one of the terminal screws 17.

Preferably formed integrally with the bracket 8 at opposite sides of its back member 19 are

2

the arms 20 which support a shaft 21 on which the tubular hub 22 of disk 23 is rotatable. The hub extends from one of arms 20 to the other, thereby spacing the disk centrally between the arms 20. However, any other arrangement for the rotatable mounting of the disk 23 will suffice.

The disk 23 is made of dielectric material. It is preferably molded to provide at suitable intervals about its periphery the embedded transversely extending rods 24 of conductive material. These rods terminate within recesses 25 as indicated in section in Fig. 4. The contact bosses 16 of the contact arms 14, 15 are receivable into such recesses 25 to engage the opposite ends of the successive conductor rods 24 which may be registered therewith by rotating the disk 23. The entry of the bosses 16 into the recesses 25 impositively defines the position of the disk in which a circuit is established from one of the contact arms 14, 15 to the other through the intervening rod. The disk can be displaced from the position of contact only by exerting sufficient rotative torque thereon to force the bosses 16 out of the recesses 25 by springing the resilient contact arms 14, 15.

At intervals between the circumferentially spaced rods 24 embedded in the disk, there are recesses 26 similar to those at 25 but having no embedded rods exposed to carry current between the contact arms 14 and 15. The recesses 26 (Fig. 5) receive bosses 16 to impositively define disk positions in which the circuit between the contact arms 14, 15 is open.

The periphery of the disk 23 projects through the conventional slot 27 of the wall plate 7 and is preferably knurled as indicated at 28 for convenience of manipulation. The disk is readily accessible, as clearly appears from Fig. 3 and, engaged by the operator's thumb or finger, may readily be rotated in either direction. The concavity of the respective recesses 25, 26 is sufficient to sharply define the positions in which the bosses 16 enter such recesses, but is not so sharp as to involve any appreciable noise as the bosses enter or leave the recesses. The disk operates smoothly and quietly. The initial resistance offered by engagement of the bosses in the recesses is easily overcome, but only after a certain amount of torque has been exerted on the periphery of the disk. Thus, there is a tendency for the circuit through the respective rods 24 to be broken with a decisive action and when one of the rods again moves between the spring contact arms 14, 15, contact will be reestablished with a decisive action due to the bias of such arms toward each other.

whereby they enter the recesses 25 with sufficient pressure to assure the proper seating of the bosses against the embedded conductor 24. The angularity between the respective spring arms 14 and 15 and their respective flanges 13 may be so determined as to be somewhat greater than 90 degrees so as to assure the desired bias of these arms toward each other.

Prolonged tests indicate that the desirable silence and smoothness of operation are achieved without the formation of any arc and without appreciable wear over long periods of time. The fact that the dielectric disk through which the conducting rods 24 extend axially has its periphery projecting through the face plate 7 for direct manual operation contributes markedly to the simplicity, economy and long life of the device.

I claim:

1. A noiseless switch, comprising the combination with an outlet box having a slotted face plate, of a dielectric disk axially supported for rotation within the box with a portion of its circular periphery exposed in said slot, said disk having its flat faces provided with annular sets of concave recesses with those of one face paired with those on the opposite face, at least one electrically conductive rod extending through the disk with its ends exposed at the bases of the recesses of one of the pairs, and resilient terminals on opposite sides of the disk, each mounted on a dielectric support and biased for pressure contact with the adjacent flat face of the disk, said terminals having embossed convex portions adapted to enter the disk recesses to hold the disk in step-by-step positions of rotary adjustment and to electrically connect said terminals when in contact with the rod ends.

2. In an electrical switch of the described class, the combination of a dielectric disk mounted for progressive step by step rotation and having an axial supporting shaft and provided with annular sets of paired concave recesses, with those of each pair oppositely disposed in the respective flat faces of the disk, at least one electrically conductive rod extending through the disk with its ends exposed at the bases of the recesses of one pair, and a set of resilient contact arms having insulated mountings and provided with embossed terminals adapted to resiliently enter said paired recesses to impositively hold the disk in each of several step-by-step positions of rotative adjustment, said terminals being electrically connected by said rod when in registry therewith, certain of said recesses presenting dielectric material to at least one of said contact arms whereby impositively to define rotor positions in which the circuit between said arms is open.

3. In an electrical switch, the combination of a rotor having dielectric faces, means supporting said rotor for unrestricted rotation in a selected direction, the periphery of the rotor being exposed for direct manual operation, opposing contacts biased toward the respective faces of the rotor, said contacts and rotor faces having coacting boss and socket means for impositively defining selected positions of said rotor, conductors embedded in said rotor for completion of an electrical circuit between said contacts at alternate rotor positions, the said rotor faces presenting dielectric surfaces to at least one of said contacts at intervening positions, whereby step by step rotation of said rotor will alternately make and break a circuit between such contacts.

4. The device set forth in claim 3 in further combination with a switch plate having a slot

through which the periphery of such rotor projects for manual operation, the arcuate extent of rotor periphery exposed through such slot comprising the only means for limiting the extent to which such rotor may be turned in a single operation.

5. The combination with a rotor, of means supporting said rotor for unrestricted rotation in at least one direction, said rotor having opposed faces and relatively fixed contacts bearing against said faces, said rotor being provided in annular series with a plurality of conductors imbedded in said rotor and adapted to complete a circuit between said contact members, portions of said rotor between said conductors presenting a dielectric surface to at least one of said contact members whereby to interrupt the circuit therebetween and to enable progressive step by step rotation of said rotor in a single direction to repeatedly make and break a circuit between said member using a plurality of successive conductors in making such circuit.

6. In an electrical switch, the combination with opposed contact members and means relatively biasing at least one toward the other, of a rotor with a peripheral portion exposed for manipulation, said rotor being disposed between said contact members and having faces against which such members are engaged, means supporting said rotor for unrestricted rotation between such members in at least one direction, said rotor having recesses in annular series upon at least one of said faces, the contact member engaged therewith having a boss coacting with successive recesses to define successive positions of said rotor, and said rotor having a plurality of means alternately dielectric and conductive between the respective contact members in the respective rotor positions, whereby progressive rotation of said rotor will alternately make and break a circuit between such members and a plurality of said conductive means will be employed to close the circuit between said members in the course of a single rotation of said rotor.

7. In a switch of the character described, the combination with a rotatable disk having end faces and a periphery manually engageable for disk rotation, of a bracket providing means supporting the disk for unrestricted rotation, and a pair of mutually insulated terminal contacts having relative bias toward each other and respectively engaging opposite faces of the disk, said disk being provided with embedded conductor means exposed at the faces of the disk in positions for simultaneous registry with said contacts in the course of disk rotation whereby the disk may be rotated by a manipulation of its periphery in either direction from any position to establish and break an electrical circuit between said terminal contacts.

8. A switch of the character described comprising the combination with a disk having end faces, one of which is provided with an annular series of recesses, means mounting the disk for unrestricted rotation in at least one direction, contact means engaging opposite faces of the disk, one of said contact means having a boss adapted to enter the successive recesses in the course of disk rotation, and a plurality of conductors embedded in the disk and extending therethrough between the opposite faces thereof, said conductors terminating in selected recesses whereby to be engaged by the said boss when said boss registers with recesses in which the said conductor ends are exposed, said contact boss and recesses

defining positions of said disk, and recesses between said conductors defining circuit-breaking positions thereof.

9. A switch of the character described comprising the combination with a bracket having mounting portions and a base portion, of dielectric supports on the base portion, contact fingers extending in mutually spaced relation from the respective supports, at least one of said fingers comprising a spring biased toward the other, said fingers having contact bosses, arms connected with the bracket, a dielectric disk provided with a mounting for unrestricted rotation between said arms and having opposed face portions with which the bosses of said fingers are engaged, said disk having corresponding recesses in annular series in its respective faces and embedded conductors terminating in corresponding recesses at selected points about said disk whereby to establish an electrical circuit between said fingers when said bosses are engaged in the recesses in which said conductors terminate, recesses of said disk between the recesses in which said conductors terminate being dead whereby to provide an off position between consecutive conductive positions of said disk.

10. The device of claim 9 in which said brackets, said fingers, said arms and said disk are enclosed in a housing, said housing having a slotted wall through which a peripheral portion of said disk projects for direct manual operation.

11. A wall switch for use in an outlet box having a slotted closure plate, said switch comprising in combination a bracket having terminal mounting portions and intermediate base and back portions, arms projecting from the back portion, a dielectric disk rotatably supported between said arms in a position such that its periphery will project through the slot of the closure plate, said disk being mounted for unrestricted rotation in either direction and having end faces provided with recesses in annular series and having embedded conductors extending axially through the disk with their ends exposed in alternate recesses of the respective series, dielectric mounts on the base of the bracket and spring terminal contact fingers disposed on said mounts

and projecting in approximate parallelism with the end faces of the disk and provided with relative bias toward the end faces of the disk, said fingers having contact bosses engageable in the recesses of the disk and between which said conductors establish an electrical connection when the rotative position of the disk is such as to register one of said conductors with the finger bosses, the intervening recesses of the disk providing dead positions in which the circuit of the end fingers is broken.

12. In a noiseless switch, the combination with a disk and means supporting the disk for free rotation in either direction, said disk having portions exposed for direct manual operation and being provided with end faces, at least one of which is dielectric, and provided with recesses in annular series, said disk including a conductor exposed at certain of the recesses of its dielectric face, of relatively non-rotatable brushes at opposite sides of said disk having relative bias toward said disk, one of said brushes having a contact portion positioned to be received into the recesses of the dielectric face of the disk in the course of disk rotation, whereby impositively to define disk positions and to contact said conductor in the recesses in which said conductor is exposed, the other brush also being provided with contact means engageable with said conductor whereby said conductor closes a circuit between said brushes when contacted thereby and the dielectric face of said disk breaks said circuit when the disk is rotated to move exposed portions of said conductor out of registry with the contact portion of the brush having the contact portion first mentioned.
